LOOSE LEAF BINDER CLAMP

Filed June 12, 1929

UNITED STATES PATENT OFFICE

AUGUST K. BRIELE AND ROBERT H. BRIELE, OF BALTIMORE, MARYLAND

LOOSE LEAF BINDER CLAMP

Application filed June 12, 1929. Serial No. 370,401.

This invention relates to loose leaf binders, and especially to an improved loose leaf binder clamp.

A disadvantage of loose leaf binders which have a key-actuated mechanism, or crank-actuated mechanism, is that the key or crank gets lost or misplaced, and the clamping mechanism cannot be operated until the key is found or replaced.

10 One object of our invention, therefore, is to provide a very practical and convenient loose leaf binder clamp including a permanently attached key or crank by which the clamping mechanism can be operated without the loss of time which has heretofore been experienced whenever the clamping mechanism is to be operated; that is, the time required for finding the key or crank.

Another object is to provide a device of 20 this character having the key or crank entirely enclosed and out of the way, within one of the tubular binder-heads, and which can be quickly and easily withdrawn or extended to the effective or operative position 25 when it is desired to use the device for clamping loose leaves.

Another object is to provide a novel form 30 of connection, for the operating key or crank, which keeps the key from rotating around the winding stem of the clamping screw when the key is fully extended or nearly so; but which permits the key to be rotated freely around the winding stem when the clamping screw has been tightened, 35 and when the key has been moved inward towards the tubular housing that receives it, so the end of the housing will not interfere with the handle or arm of the key when being slid into the housing.

Another object is to provide a device of 40 this character in which the key or crank extends sufficiently from the tubular binder-head, when in its inoperative position, to enable the user to grasp it with a thumb and finger and thereby withdraw it into the operative position; and a further object is to provide the primarily open end of the tubular binder-head with a hollow or concaved 45 hinged closure member, and to provide such

closure member with a catch for holding it in its normal closed position.

Other objects and important features are pointed out or implied in the following details of description, in connection with the 55 accompanying drawings in which:

Figure 1 is a top plan view of the device embodying our invention, the greater part of the covers and leaves of the book or binder being broken off, and the key or crank being extended to its operative position. 60

Figure 2 is an end view of the device shown in Figure 1, the hinged cap or closure being in the wide-open position.

Figure 3 is a view similar to Figure 1, 65 except the top plate of the tubular clamping head being removed, that is, the binder-head which contains the clamping mechanism and the operating handle or crank, the latter being in its operative position. 70

Figure 4 is a view similar to Figure 3, but parts being broken off, and the operating crank being in its concealed or out-of-the-way position, and the hinged closure being in its closed position. 75

Figure 5 is an enlarged sectional detail view of the operating key or crank in its operative or fully extended position on the winding stem (of the screw-rod or clamping screw) on which the tubular body of 80 the key is slidably mounted.

Referring to these drawings in detail, in which similar reference characters correspond to similar parts in the several views, and in which the hinged covers 10, the tubular binder-heads 11 and the hinge 12 thereof are of previously known construction, the invention is now described in detail as follows:

Each tubular binder-head is provided 90 with circular openings, as indicated in dotted lines at 13. One of these openings is fitted with a guiding member which is tubular, that is, one at each end of the tubular member 11 which is shown open in Figure 3. These guiding members are indicated at 14, and through them, chains 15 extend into the interior of this tubular guiding member. These chains 15 may be properly considered as jointed binder-posts, for 100

one end of each chain is secured to the binder-head which co-operates with the one having the guides 14 therein, while the other end of each chain or flexible member 15 is connected to nuts or connections 16 by means of links 17 and rivets 18.

A screw-threaded rod 19 is journalled, at 20 and 21, in the tubular binder-head which has the guides 14 therein, and this screw-rod has left-hand threads extending from 10 one end to its middle part, and right-hand threads extending from the other end to its middle part. The nuts or connections 16 have right-hand threads and left-hand threads, respectively, which are meshed with 15 the corresponding threads of the screw-rod, and when the latter is turned, the connections 16 are thereby moved in opposite directions along the interior of the binder-heads which contains them. It will be seen, therefore, that when the screw-rod is turned, the parts 15, 16, 17 and 18 combine for drawing 20 the binder-heads 11 towards one another for effecting the clamping of loose 25 leaves between them.

The mechanism thus far described is of previously known construction, except that in such previously known construction, the bearing 21 is similar to the bearing 20 and nearer the end of the binder-head. Moreover, the screw-rod in this present invention has an extension 22, that is, a reduced part beyond the threads of the screw-rod. In such previously known devices, both ends of 30 both tubular binder-heads are closed by permanently fixed caps or covers such as shown at the lower ends of Figures 1 and 3, whereas, the present invention includes a hollow or concaved cover or closure 23 which is hinged 35 at 24 and is provided with a spring-catch 25. In consequence of the bearing 21 being at a distance from the originally open end of the binder-head which contains it, a storage 40 space 26 is provided in this binder-head and in the hollow of the closure 23. The purpose of this storage space is to receive the handle of the operating member or crank which includes a tubular shank 27 and an L-shaped handle member 28. This crank or 45 handle member includes the handle and a shank, which latter is slidingly fitted in a radially disposed bore 29 at the outer end of the tubular shank 27, which latter has a laterally disposed notch 30 which receives a lug or flattened end portion 31 of the member 28. It will be seen, therefore, that the 50 member 28 can be slid longitudinally for engaging and disengaging the lug 31, and that when each lug is engaged with the notch 30, the handle member 28 is held rigid with the shank 27, so the latter can be turned for 55 turning the screw-rod; and in this connection, it should be understood that the extension or winding stem 22 of the screw-rod extends into the interior of the tubular shank 60

27, so that the latter is slidable thereon, from its outer or operative position, to its inner or inoperative position. The foregoing is made clear by the illustration in Figure 4, where the key member 28 is turned through 180° from the position shown in Figures 1 and 3, and where the shank 27 is shown in its innermost position. Moreover, by referring to Figure 4, it is seen that the end of the crank extends sufficiently far beyond the end of the tubular binder-head 11 to enable the user to grasp it with a thumb and finger when the cap or closure 23 is opened. Moreover, it is seen that the cap 23, when closed, receives this projecting end of the 70 crank, and combines with the storage space 26 to provide a normally closed hollow casting for completely enclosing the crank. The shank 27 is provided with a pin or stop 32 which extends excentrically therethrough and bears against a slabbed side 33 of the extension 22, and prevents rotation of the crank relative to the screw-rod, while permitting the crank to slide longitudinally, inward and outward, to the extent limited 75 by the stop 32 and the shoulder 33a at the outer end of the slabbed side 33. A reduced cylindrical part 22a has one side flush with the slabbed side 33, so the pin 32 slides easily from the slabbed side to this reduced cylindrical part; and when out of engagement with the slabbed side 33, the pin 32 can turn around the reduced cylindrical part. By 80 means of this novel operating key connection, the user can draw the key out until the pin 32 and slabbed side are cooperative for turning the clamping screw until the leaves are clamped securely, whereupon the key can be slid inward; and if the handle member is then out of its proper relation to enter the tubular housing 11, it can be turned when the pin 32 has passed inward beyond the slabbed side 33, then moved to its innermost 85 position shown in Fig. 4.

Although we have described this embodiment of our invention specifically, it is not our intention to limit our patent protection to these exact details of construction and arrangement, for the invention is susceptible of numerous changes within the scope of the inventive ideas, as implied and claimed; for instance, the invention is not limited to the pin and slabbed side connection 32—33, for other means may be employed for the same purposes explained above.

What we claim as our invention is:

1. In a loose leaf binder clamp, the combination of a tubular binder-head having openings between its ends, a screw-threaded rod journalled in said tubular binder-head and extending substantially from end to end thereof, connections threaded on said rod and thereby movable along said tubular binder-head, flexible members connected to said connections and extending through said 125

openings and adapted to be pulled inward by said connections and provided with a leaf-clamping member movable toward the said binder-head for cooperation therewith, 5 and an operating member including a handle and being adjustably secured to said screw-threaded rod so as to be movable from its operating position into such position that said handle is within the said tubular binder-head.

2. In a loose leaf binder clamp, the combination of a hollow casing including a tubular binder-head having openings between its ends, a screw-threaded rod journalled in said binder-head and extending substantially from end to end thereof, connections threaded on said rod and thereby movable along said binder-head, flexible members connected to said connections and extending 15 out through said openings and provided with a leaf-clamping part to be pulled inward for cooperation with said binder-head, and a crank having a handle, said crank being on one end of the screw-threaded rod and 20 operable to turn the latter and to be slid longitudinally thereof to a position for storing its handle in said hollow casing.

3. In a loose leaf binder clamp, the combination of a tubular binder-head having 30 openings between its ends, a screw-threaded rod journalled in said binder-head and extending substantially from end to end thereof, connections threaded on said rod and thereby movable along said binder-head, 35 flexible members connected to said connections and extending out through said openings and provided with a leaf-clamping part to be pulled inward for cooperation with said binder-head, and a crank including a 40 handle and a tubular shank, said tubular shank inclosing one end of the screw-threaded rod and operable to turn the latter and to be slid longitudinally thereon from its 45 operative position to a position for storing its handle in said tubular binder head, substantially as specified.

4. In a loose leaf binder clamp, the combination of a tubular binder-head having openings between its ends, a screw-threaded 50 rod journalled in said binder-head and extending substantially from end to end thereof, connections threaded on said rod and thereby movable along said binder-head, 55 flexible members connected to said connections and extending out through said openings and provided with a leaf-clamping part to be pulled inward upon rotation of said screw-threaded rod, and a crank including a tubular shank and an L-shaped handle-member, the latter being journalled in said 60 tubular shank and turnable from its operative position to an inoperative position in which it extends towards said tubular binder-head, said tubular shank enclosing an extended end of the screw-threaded rod and

operable to turn the latter and slideable from its outer position to its inner position in which the said handle-member is almost wholly within said tubular binder-head.

5. In a loose leaf binder clamp, the combination of a tubular binder-head having 70 openings between its ends, a screw-threaded rod journalled in said binder-head and extending substantially from end to end thereof, connections threaded on said rod and thereby movable along said binder-head, 75 flexible members connected to said connections and extending out through said openings, a second binder-head secured to said flexible members and adapted to be pulled inward thereby upon rotation of said screw-threaded rod, a crank on one end of said screw-threaded rod and operable to turn the latter and movable thereon from its operative position to a storage position almost 80 entirely within said tubular binder-head, and a closure having a hollow side to receive a slightly projecting part of the crank, 85 said closure being hinged to the tubular binder-head in a position to close the end that receives the crank and to combine with said end for entirely enclosing the said 90 crank.

6. In a loose leaf binder clamp, the combination of a tubular binder-head having 95 openings between its ends, a screw-threaded rod journalled in said tubular binder-head and extending substantially from end to end thereof, connections threaded on said rod and thereby movable along said tubular 100 binder-head, flexible members connected to said connections and extending through said openings and adapted to be pulled inward by said connections, a second binder-head secured to said flexible members and thereby movable towards the first said binder-head, 105 a manipulative member adjustably secured to said screw-threaded rod so as to be movable from its manipulative position into the interior of said tubular binder-head, said manipulative member including a tubular shank, said screw-threaded rod having a winding stem that extends into said tubular shank, said winding stem having an outer part including a slabbed side, said winding 110 stem having a reduced cylindrical inner part adjoining the slabbed side, and a stop disposed eccentrically in said tubular shank and adapted to combine with said slabbed side for turning the screw-threaded rod, the 115 said stop being turnable around said reduced cylindrical part when the manipulative member has been slid to a position between its outermost and innermost positions, for the purpose specified.

In testimony whereof we affix our signatures.
